Application May 27, 1931, Serial No. 546,328. Renewed October 25, 1934. In Germany May 27, 1931.

1 Claim. (Cl. 33—111)

The present invention relates to a pantograph comprising rules that can be joined together and serve for enlarging or reducing drawings and plans.

5 The existing instruments for copying drawings, plans or the like to a predetermined scale suffer from serious drawbacks. Reducing rules, for instance, can accommodate only two scales which must have the same subdivision. Polar
10 pantometers subject the eyes of the draftsman to severe strain. The radial pantometer produces a copy turned 180°, the production of which requires much practice. Proportionally adjustable reproducing instruments like the
15 reducing compasses and the pantograph have in common one important advantage, namely, the mechanical reproduction of the measures wanted, but this involves also the drawback of insufficient control of measurements. Other
20 defects of reducing compasses are the small range, insecure work at large compass opening, easy variability of the clamping, and the spoiling of both the original and copy by piercing. Pantographs, on the other hand, are expensive,
25 require a large and absolutely plane drawing table, need much practice and are bothersome to start and, owing to their bulk and weight, difficult to pack.

The invention eliminates these drawbacks by providing two independent rules which are fixed with their opposite zero points in a common point.

The instrument according to the invention is illustrated in the accompanying drawing, in which Figure 1 is a top view thereof; Fig. 2, a longitudinal view thereof; and Fig. 3, a side view.

Referring to the drawing, A and B are the rules, the scales chosen for example being 1: 1000 for A and 1: 2500 for B. The rules A and B consist of strips of a material that is as unchangeable as possible to insure permanency of the divisions made thereon. To adhere closely to their support, the strips are thin and elastic, while their width depends on their length but must be large enough to insure straightness of the edges. The strips may differ in length. The longer they are, the greater will be their range and the strain to which the means for holding them together is subjected. Each strip has a different division extending from left to right and arranged in corresponding position on both edges.

If the strips forming a set are of equal length, 55 the strip for the larger drawing will be used

over its entire length and that for the smaller drawing only partly. To prevent trouble due to the unused portion of the second rule, the part concerned is preferably covered with a narrow strip of a suitable material, such as leucoplast which can be removed readily without leaving traces.

The joining of the strips is made possible by surrounding the zero points v of both edges with circular projections v , in the center of which, i. e., in the zero point itself, apertures are provided for the pin d . Each of the strips is formed with two of said circular projections v at one end thereof, one of said two projections being in the plane of the strip and the other being offset in a plane parallel thereto to the extent of the thickness of the strip. This arrangement of the projections v permits coupling of the two strips in the same plane.

Horizontal displacement is prevented by the pin *d*, which should offer as little resistance as possible, or a pin inserted in the drawing table. Vertical lifting of the coupling is prevented by the rubber ball pierced by the pin *d* and pressed down onto the coupling point. 25

The rules according to the invention are very simple to use. After it has been determined what ratio between the original and the reproduction is desired the corresponding pair of measuring strips A and B are chosen. It is determined whether the copy can be made from one point or graticulation is necessary. In the latter case, the mark on the strip for the larger drawing indicates half the width of the squares for the largest possible graticule. The original is then placed on the table and covered with transparent tracing paper for the reproduction. 35

If a graticule has been prepared, the first cross of the graticule of the tracing paper is placed over the corresponding cross of the original so that both are in perfect registry. Then the strips A and B are coupled, preferably by placing the original A below and B on top of it, so that the top edge of A and the lower edge of B are fixed. If a graticule has been used, the zero points of these two edges are placed over the first cross and fixed to the table exactly at the intersecting point by the pin *d* or a suitable other means whereupon the rubber bulb *g* is pressed down onto the coupling. Reproduction is effected by gauging a point of the original with A and reading the distance from the zero, whereupon B is softly contacted with A which is then moved away instantly. Now the previously read distance is determined

on B, the working edge of which occupies the position of the A-edge, and transferred to the reproduction. This process is repeated until the reproduction has been completed.

- 5 The device according to the invention permits working even within a very limited space, protects the plans and the like by dispensing with auxiliary lines or the like, can be easily handled without previous instruction and requires only
10 one-fifth to one-tenth of the time now needed to effect a reproduction. Furthermore, it insures absolute precision in reproducing a copy showing the same direction as the original, permits an excellent control of the progress of
15 the work and instant checking of any errors

or inaccuracies, is very handy owing to its slight dimensions and weight and can be produced at a very low cost.

We claim:—

5 A pantograph device comprising two rules adapted to be detachably connected together at one end and to a drawing board while disposed at an angle to each other, said rules having associated scales thereon, the scales of 10 each rule having corresponding indicia but different spacing for enlarging or reducing drawings.
